METHOD AND MEANS FOR EMITTING SIGNALS WITH VARYING SIGNAL CHARACTERS

Erik Robert Parsberg, Lidingo, near Stockholm, Sweden, assignor to American Gas Accumulator Company, Elizabeth, N. J., a corporation of New Jersey

Application December 22, 1932, Serial No. 648,348
In Sweden December 24, 1931

9 Claims. (Cl. 177—352)

It has become the general practice in arranging the illumination of air routes to use powerful revolving searchlights projecting beams of condensed light which sweep the horizon. When 5 these beams of light sweep past a certain point, the impression obtained in the said point is that of a flashlight character, usually single flash. The period between the separate flashes varies in length in different countries. In America, for 10 instance, it is considered sufficient with one flash every 10 seconds, whereas in Germany they have generally gone in for a period of about three seconds. If it is taken into consideration that it has been the practice for decades of years to provide 15 one flash every five seconds for the marine traffic which moves very much slower, the conclusion is easily arrived at that for aviation the period should be quicker and not slower, and consequently that a period of 3 seconds would be 20 more in accordance with the requirement of the air traffic.

Flashes at shorter intervals may be obtained by increasing the rotary speed of the apparatus or by dividing the available light energy into 25 several beams. In both cases the efficiency of the beacon will be reduced. In the first case the light impression will be diminished owing to the reduced duration of the flash (according to the Blondel and Rey law), while in the latter case 30 the light efficiency of the beacon will be reduced by the said division of the light energy.

The Frenchmen Blondel and Rey have scientifically proved that in order to obtain a flashlight of a light range equivalent to that of fixed light, the light power of the flashlight must be larger and must consequently be multiplied by a factor which is less than 1. This factor is dependent on the duration of the flash and diminishes quickly as this is reduced. The factor in question is, 35 for instance, approx. .2 for a flash of .03 sec., .48 for a flash of .1 sec. and rises to .84 for a flash of .3 sec.

From this point of view it would be advantageous 40 in order to obtain a good light impression or a good signal effect to have a long duration of the flash, which can be attained by increasing the width of the light beam or by reducing the rotary speed of the beacon. From the point of view of light economy the first mentioned way of 45 solving the question is however not to be recommended. On the other hand a reduction of the rotary speed will mean that the interval between the separate flashes will be longer. As stated above it is, however, desirable that this interval 50 should be comparatively short.

It is thus evident that the two requirements which at present present themselves particularly in the technique of airway beacons, i. e. long duration of the flash on the one hand and short intervals between the separate flashes on the other, are at variance with each other, inasmuch as the compliance with one of the requirements requires a low rotary speed whereas the other requires high rotary speed of the beacon.

This invention refers to an arrangement by 10 means of which the above mentioned features are both attained simultaneously, the lens or reflector system of the beacon being so arranged as to rotate or oscillate with a revolving motion in such a way that the signal character of the beam or 15 beams of light will be different in different directions. According to the invention this purpose is obtained thereby that the lens or reflector system of the beacon is not allowed to revolve uniformly as has been the practice hitherto, i. e. 20 with an approx. constant speed and all the time in the same direction, but is instead given a non-uniform revolving motion. By non-uniform revolving motion is to be understood in this connection that in certain sections of the revolution the 25 system either revolves at a slower speed than in other sections, or else changes revolving direction, i. e. performs an oscillating motion comprising certain sections.

The intention with such a non-uniform revolving motion is to improve the light impression in certain sections of the revolution at the expense of the light impression in the other sections. When the beacon is intended as an airway beacon 30 the flying direction is suitably laid through the first mentioned sections because the beacon light should be most visible in that direction whereas the other sections do not as a rule require full 35 light power.

In one form of employing the invention the lens or reflector apparatus is, as mentioned above, given a lower angular speed when the beam or 40 beams of light sweep past the flying direction and a higher angular speed when the same beams sweep past sections outside the flying direction. In this way the duration of the flash time will be 45 longer in the sections through which the flying direction is laid, whereas it will be shorter in the other sections. A beacon having two lens panels 50 arranged at an angle of 180° between their optical axis, and giving at a constant revolving speed and a period of, say, 5 seconds a flash of a duration of .10 sec., thus will be arranged successively to alter the revolving speed. When 55

beams of light from the lens panels pass the flying direction the speed of the beacon has been reduced to one third, whereas the speed has been increased three times when the same light beams pass directions which are at right angles to the flying direction. Then the light efficiency of the beacon in the flying direction will successively be increased by about 80%, whereas the light efficiency in directions which are at right angles to the flying direction will successively be reduced to about half.

Fig. 1 on the attached drawings shows a light efficiency diagram of such a beacon, i. e. a polar diagram, showing the effective light power or the light power, transformed according to the Blondel and Rey law. The curve *a* represents the limit curve for the light efficiency of a beacon revolving at a periodically varying angular speed. As is seen, maximum and minimum light efficiency respectively, is obtained in two diametrically opposite directions *b*—*b* and *c*—*c*, respectively, which correspond to minimum and maximum speed, respectively. The direction *b*—*b* is the flying direction. For the sake of comparison curve *d* shows the light efficiency of the same beacon revolving at the same time per revolution but at constant angular speed.

In the above given example the light efficiency curve will thus have the approximate appearance of an ellipse, the major axis of which, *b*—*b*, is about three times as long as the minor axis *c*—*c*. The aviator should naturally try to keep the direction in which the flash is of the longest duration.

In another form of employing the invention, suitably also arranged with 2 lens panels with 180° between the optical axis, the lens or reflector apparatus is given an oscillating angular motion in the horizontal level, whereby the light beams will sweep a certain section through which the flying direction is laid.

Fig. 2 shows a diagram of the light efficiency and the light character of a beacon, the revolving motion of which comprises an angle of approx. 90°. The shadowed field inside curve *e* shows the light efficiency, whereas curve *f* is a vector diagram by means of which the light character in different directions is easily read. If a vector *g* is drawn this will intersect curve *f* in various points *h*, which correspond each to one flash. The space between these points is proportional to the eclipses between the flashes. In the case shown it is thus seen that two flashes *h* are obtained in succession, separated by a slightly longer dark period. The closer you come to the flying direction *i*—*i* or *i*¹—*i*¹, i. e. the sides of the revolving angle, the more the two flashes will melt into one long flash *h*¹. On the other hand, in the direction of the bisectrix *j*—*j* of the angle a light character is obtained in which the flashes recur at equal intervals. In this way the character of the beacon can be read from the diagram in any direction.

The character of the beacon will thus alter during the revolving motion, single flash character being obtained in the centre of the section. From the centre towards the edges the single-flash character changes gradually into a double-flash character that becomes more and more pronounced, until the two flashes following close on each other melt into the long flash *h*¹ at the extreme edges. The aviator should naturally try to fly in the direction in which the last mentioned long single-flash character is seen.

A larger or smaller improvement of the light

economy is obtained depending on the size of the angle or section that the beacon light has to sweep. If this angle is chosen to be 90° or $\frac{1}{4}$ of a revolution for instance, as shown by Fig. 2, an amount of light is emitted within that angle which is 4 times larger than if the beacon were revolving 360°, i. e. a complete revolution. This increased amount of light may be utilized to improve the signal effect of the beacon either by increasing the duration of the flash or by reducing the time between the flashes, or by both.

The sections of the revolution that are not swept by the said main beacon light lie outside the flying direction and should not require any lighting in normal flying. Should this be desired, however, in some case, a weaker secondary light can easily be arranged at *k* in the way known before.

The revolving angle of the oscillating motion according to Fig. 2 can, if desired, be increased to 180°. If this is done and the flying direction is laid along the turning points of the revolving motion single flash is obtained in the flying direction, whereas double-flash character is obtained as soon as the aviator deviates from the flying direction, as will be understood from the diagram in Fig. 2. In order to avoid collision of meeting aeroplanes the aviator should in this case, always keep to starboard of the beacon, i. e. the pilot should always keep inside the angle of the double-flash character, but as near the direction of the single-flash character as possible.

The revolving angle may also be larger than 180°, as shown by the diagram, Fig. 3. One of the diagrams, showing the light character of the two lens panels, is drawn with complete lines *l*, whereas the other diagram, pertaining to the other lens panel, is marked with dotted lines *m*. From this diagram it is exceedingly clear that in the angle *a*, which is swept by the light beams from both of the lens panels, the flashes will occur twice as frequently as in the other sections. If a radius is drawn within this angle, the following character is obtained: two flashes following close on each other—one dark period—two close flashes—etc. The flying direction is therefore suitably laid within this angle *a*.

If the flying route is laid along one of the legs of the said angle two aeroplanes coming from opposite directions cannot collide, provided that both aviators keep inside the angle *a*, in which the close-double-flash character of the beacon in front of them is seen. From Fig. 3 is also seen that the light efficiency curve *n* in this case will be an ellipse.

In a third way of using the invention the lens or reflector apparatus is given a horizontal revolving motion, which is discontinued one or several times during each revolution, changing into an oscillating motion comprising a certain angle, thereafter to continue again as a revolving motion. Fig. 4 shows a diagram of the light character in this case. As is seen, the oscillating motion takes place within the angle *s*. In the centre of this angle three flashes following in succession are obtained, which towards the edges of the angle gradually change into one long and one short flash *o* and *p*, respectively. Outside the angle *s* ordinary uniform single-flash character is obtained.

The flying direction should be laid within the angle *s*.

Fig. 5 shows a diagram according to which two lens or reflector apparatus placed, for instance, on top of or beside each other move back and

forth within the same angle but in opposite directions, as indicated by the light character curves z^1 and z^2 of the respective apparatus. Single flash with long flashes is obtained in the turning points z^3 and z^4 of the revolving motion, respectively, whereas a more or less pronounced double-flash is obtained between the turning points except at the centre of the angle, where single flash is obtained.

10 Similar forms of employing the invention with two diametrically opposite light sections are particularly well suited for airway beacons placed along coasts where no light is desired towards the sea.

15 In another form of employing the invention two lens or reflector apparatus are co-operating, one of which revolves whereas the other turns back and forth within an angle of any size, as is shown by the curves z^5 and z^6 , respectively, Fig. 6.

20 Within the revolving angle γ of the last mentioned apparatus and outside this angle, respectively, different light characters may be obtained by adjusting the motion of the revolving lens apparatus in relation to the oscillating motion, as is shown to the left and to the right, respectively, in the diagram Fig. 6. From the diagram to the left is seen that the aviator receives a mixed single and double flash character furthest out towards starboard and three-flash character

25 furthest out towards the port side. Outside the revolving angle γ a slow single-flash character is obtained in relation to the character within the said angle. The revolving angle γ is the limit of the flying route. If the connecting line between 30 two such beacons is laid along one of the legs of the revolving angle γ there can be no collision of aeroplanes coming from opposite directions, provided that the pilots always keep inside the angle γ of the beacon in front of them.

40 In this form of employing the invention the character within the flying angle γ can be very rapid and alterations in the character are thus easily noticed.

45 Lights of the description in question make the use of special so called "course lights" unnecessary because the aviator will notice an alteration in the flying character as soon as he deviates from the flying course.

The above described forms of arranging the 50 light may naturally also be used for maritime beacons, or for maritime and airway beacons combined.

55 On the attached drawings some constructive examples of employing the idea of the above mentioned invention are shown. The first form of employing the invention, according to which the lens or reflector apparatus revolves at a periodically varying angular speed, is shown in Figs. 7-15. With such arrangements the efficiency diagram according to Fig. 1 is obtained. Figs. 16

60 and 17 show some forms of arranging so as to provide for an oscillating motion comprising a certain angle, corresponding to diagram Figs. 2 and 3. Figs. 18 and 19 show an arrangement 65 in order to provide for a horizontal revolving motion, which is interrupted and replaced in certain moments by an oscillating motion, corresponding to the diagram Fig. 4. According to Fig. 20 the lens or reflector system is divided in two parts

70 which move in relation to each other, corresponding to the diagram Fig. 5. In the arrangement according to Figs. 21, 22, 23 the lens system is divided in two parts, one of which revolves and the other turns back and forth within an angle 75 of any size, corresponding to diagram Fig. 6.

Fig. 7 shows a vertical section through a lens apparatus whereas Fig. 8 shows a horizontal section of the same apparatus along the line A-B. Two lenses, for instance Fresnel lenses, 1, 2, are supported by a foundation plate 4 connected to a 5 vertical revolving shaft 3. Inside the lenses a source of light is arranged in this case consisting of an electric incandescent lamp 5, the light from which is refracted by the lenses 1 and 2 in such a way that one beam of light is reflected from 10 each one of the lenses, as indicated by the dotted lines. On the shaft 3, resting in the bearing 6 at the fixed foundation 7, a revolving screw wheel 9 is placed, which gears with a worm 8. The worm 8 is connected to a suitable source of power, for 15 instance an electric motor, which causes the worm to revolve at a constant speed. As is shown, the screw wheel 9 is cast in one piece with or in some other way connected to an eccentric geared elliptic cog-wheel 10 which is also placed on the shaft 20 3 and which engages with an eccentric geared elliptic cog-wheel 11 of the same size, this latter wheel, as well as a cylindrical cog-wheel 12 that is firmly secured to the cog-wheel 11, being placed on an intermediate shaft 13 arranged at the foundation 25 7. The cog-wheel 12 is arranged to gear with a pinion 14 wedged on to the shaft 3. If the worm 8 revolves at a constant speed it is evident that the intermediate shaft 13 will receive through the elliptic gear 10, 11 a periodically varying angular speed, which after gearing to about half by 30 means of the cylindric gear 12, 14 is transmitted to the shaft 3 and the lens system connected to same. By the reduction of the speed, the speed cycle is repeated twice in each revolution of the 35 lens system, whereby, as shown by the diagram Fig. 1, minimum and maximum value of the light efficiency will be obtained in two directions which are at right angles to each other.

In order to provide for the desired periodically 40 varying speed of motion any known arrangement intended for such purpose may be used.

Amongst the great number of such arrangements the following additional examples may be 45 mentioned here:

Fig. 9 shows a horizontal section of a lens system similar to the one described above, to which a periodically varying revolving motion is transmitted by means of a link mechanism. On the driving shaft 15 a link 17 is placed, on which 50 there is a groove 16. In this groove a journal for another link 18 slides, this latter link 18 being placed on a shaft 19 connected to the lens system. If the shaft 15 is caused to revolve at a constant speed, the link 17 will be included in this motion 55 and the journal for the link 18 will slide back and forth in the groove 16 at the same time causing the shaft 19 to revolve. It is evident that this shaft will thereby be caused to revolve at a periodically varying speed, seeing that its momentary 60 speed depends on the angle between the two links.

Fig. 10 shows schematically a Cardanic link arrangement serving the same purpose as the above described transmission mechanisms. The driving shaft 20, resting in fixed bearings 23, is arranged 65 in an inclined position in relation to the shaft 21 which is connected to the lens system and rests in a bearing at 24. The two shafts are connected by means of a universal joint 22. When the shaft 20 is revolving at constant speed the shaft 21 will, 70 as is known, be caused to revolve at a periodically varying speed.

Fig. 11 shows schematically another arrangement for transformation of a uniform revolving motion into a periodically varying motion. On 75

the driving shaft 28 a cog-wheel 26 is secured in an eccentric position, this cog-wheel engaging with a pinion 27, which in its turn gears with a third cog-wheel 28 placed on the shaft 28 connected to the lens system. The pinion 27 is supported by two arms 30, 31 turning around the centre of the pinion, one of these arms, 30, turning around a journal 32 in the centre of the wheel 26, whereas the other arm 31 turns around the shaft 28. If the shaft 28 revolves at constant speed, the cog-wheel 26 will turn eccentrically around this shaft, but the gearing with the intermediate pinion 27 as well as the gearing between this pinion and the cog-wheel 28 is maintained because simultaneously with the rotation of the wheel 26 the pinion 27 is moved by means of the arm 30. The pinion 27 will thus roll back and forth along a part of the periphery of the wheel 26, whereby this wheel will be caused to revolve at a periodically varying speed. If a suitable eccentricity of the wheel 26 is chosen and the three cog-wheels are of suitable size in relation to each other this motion may also be caused to change direction periodically.

28 A further arrangement for the same purpose is shown in Figs. 12, 13, 14 and 15. Fig. 12 is a vertical section through a lens apparatus and the driving mechanism belonging to it, whereas Fig. 13 is a horizontal section through the latter along the line C—D. On the driving shaft 32, resting in a bearing in the frame 7, a disk 33 is secured, in which there is a cam or guiding groove 34. In this groove, bordering on the edge 35 of the disk, a roller 36 slides which is arranged at a piece 37 of the shape of a crank on the shaft 38 connected to the lens apparatus. The crank 37 is arranged above the disk 33 in such a way that the crank does not prevent the disk from turning. When the disk 33 turns at a constant speed the roller 36 is obliged to follow the groove 34 whereby the shaft 38 is also caused to revolve. The angular speed of the crank 37 in different moments depends naturally on the shape of the groove 34. In order to obtain the intended periodically varying speed with two speed cycles during each revolution of the shaft 38 the groove should be shaped approximately as a heart. By making an indentation in the groove for instance at 39 the angular speed of the crank 37 may be reduced in that place to 0, or the crank may even be made to move backwards along a certain angular arc in each half of the revolution.

55 In the position of the disk 33 and the crank 37 shown in Figs. 12 and 13 the latter does not receive any revolving component of force when the disk 33 revolves. In order to move the crank out of this dead position a knob 40 is arranged on the disk 33, this knob co-operating with a corresponding knob 41 on the crank 37 in such a way that when the disk 33 turns the knob 40 causes the crank to leave the dead position. The position of the roller 36 in the groove 34 will thereafter be such as to cause the shaft 38 to revolve when the disk 33 turns. In order to make the roller continue to follow the groove at the apex of the "heart" when the disk 33 has turned 180° (Fig. 14) a pawl 42 is arranged, which is normally kept in such a position by a spring 43 that the groove is blocked. When the roller 36 arrives at the pawl this is pushed aside by the roller and the roller is thus forced into the apex of the groove (see Fig. 15). When this has been done the spring 43 can push the pawl back and the roller 36 continues to move in the groove.

75 Fig. 16 shows a horizontal section of an ex-

ample of an arrangement intended to provide for an oscillating motion of the lens system. On the driving shaft 46 a cam disk 47 is placed, arranged in such a way as to guide an arm 49 secured on the shaft 48 of the lens system. When the shaft 46 revolves the shaft 48 will in this way be turned back and forth over a certain angle. Constant angular speed may suitably be obtained if the cam disk 47 is shaped as an involute. If the motion is desired to comprise a larger angle 10 than 90° an intermediate shaft 49a should be arranged, according to Fig. 17, between the cam disk 47 and the shaft 48, this intermediate shaft 49a being fitted with a cogged segment 50 which engages with a cogged wheel 51 on the shaft 48, 15 the segment co-operating with the cam disk 47. By choosing a suitable relation between the gearing of the cogged segment 50 and the cogged wheel 51 the desired revolving angle of the lens apparatus is obtained. 20

In Fig. 16, the corresponding diagram of which is shown in Fig. 2, 72 is the lens for emission of the secondary light shown at k in the diagram.

An oscillating motion may naturally be obtained also in other known ways, for instance by 25 means of a crank and connecting rod, a crank and slot or the like which will be evident without any special drawings.

Fig. 18 shows an arrangement intended to give the lens apparatus a revolving motion, which 30 is interrupted and replaced in a certain or certain angles of each revolution by an oscillating revolving motion. Fig. 19 is a section through the driving device. A driving shaft 58 is arranged in such a way that the lens apparatus will 35 be included in the rotation of the shaft by means of friction in the bearing 57 of the disk 58 supporting the lens apparatus or by means of a special friction clutch. The disk 58 is provided on the underside with a number of pins 59 spaced in 40 a certain way, for instance two pins in diametrically opposite places. While the disk 58 is revolving these pins will be caused to co-operate in a certain position with a cam disk 60, rotating in the same direction as the disk 58. Owing to 45 this co-operation the disk 58 will be moved backwards during a certain part of the revolution but will thereafter continue its original motion. During the motion backwards there will naturally be some slipping in the bearing 57 or in the 50 friction clutch. The cam disk 60 is caused to move by means of the shaft 66 via three cog-wheels 61, 62, 63.

A similar motion can also be obtained by means of the arrangements shown in Figs. 11, 12, 13. 55

Fig. 20 shows a lens apparatus cut in two halves by a horizontal plane through or near the focus of the lens system. The lower lens part 73 rests on the disk 64, placed on the vertical driving shaft 65. The upper lens part 74 is supported by the 60 rods 66 which are secured to a table 67 revolving around the shaft 65. On the shaft 65 and the table, respectively, the conical cog-wheels 68 and 69 are arranged, which gear with a common conical cog-wheel 70. If this latter cog-wheel is 65 caused to revolve, the upper and the lower parts, 74 and 73, of the lens apparatus will revolve in opposite directions. A periodically varying motion may simultaneously be obtained by connecting any of the above mentioned motion mechanisms to the shaft 71 of the cog-wheel 70. As is shown, this mechanism consists in this case of an inclined universal joint. 70

By the said division of the lens one common source of light may be used, which is advantageous 75

both from an economic point of view and from the point of view of safety as compared to the arrangement hitherto used in such cases of providing each part of the lens with a separate source of light. If in the latter case one of the two light sources should go out the beacon would show a false character.

Fig. 21 shows a further form of employing the invention with two lens apparatus arranged one on top of the other, one of them revolving and the other oscillating. Same as in Fig. 20, the upper part 74 is supported by the rods 66, which are secured to a table 67 revolving around the shaft 65. The lower lens part 73 rests on the disk 64 placed on the shaft 65. The table 67 and the upper lens part 74 are caused to revolve at a periodically varying revolving speed by means of the elliptic gear 76, 77 driven by the shaft 75. The lower lens part 73 on the other hand is caused to move back and forth by means of the cam disk 78 arranged on the shaft 75 co-operating with the arm 79, secured on the shaft 65. Instead of these driving mechanisms some of the other arrangements previously described may be used.

Fig. 22 shows a section along the line GH, while Fig. 23 shows a section along the line I—K in Fig. 21.

In the diagrams hitherto shown, at least one lens or reflector system rotates with a non-uniform speed. Indeed the same result also may be obtained by means of two or more lens or reflector systems, rotating with different speed or in different direction or both. In the diagram shown in Fig. 24 two lens parts placed, for instance, on top of or beside each other, are supposed to revolve in opposite directions but at the same speed. The light efficiency curve is shown at q , from which is seen that a very marked increase in the light range is obtained at q^1 and q^2 , in which points of the periphery the light beams from the two lens parts coincide. The curve r indicates the light character of one of the lens parts, while the curve s indicates the character of the other part. It will be realized that double-flash is obtained everywhere except in the direction $t-t$, where the light beams from the two lens parts coincide and where a long single-flash character is obtained. In addition, a twice as rapid single-flash character is obtained in the direction $t'-t'$ at right angles to $t-t$, but in that direction the duration of the flash will only be half as long as in the direction $t-t$.

It is easy for the aviator to follow the exact flying route, which is suitably laid in the direction $t-t$, with a deviation of a few degrees only, because as soon as he leaves the route, flying for instance to the right of it, he will notice a light beam coming from the right first, quickly followed by a light beam from the left, i. e. double-flash character will be obtained. If deviation takes place to the left, double-flash character is also obtained, but in that case the first flash will come from the left followed by a flash from the right.

The lenses may naturally also be made to revolve at different speed in opposite directions, as is shown in the diagram Fig. 25. As is seen, the light character will in that case be more complicated. u represents the light character curve of one of the lens parts and v the curve of the other lens part.

According to the diagram Fig. 26 two lens parts are supposed to revolve in the same direction but at different speeds. x and y , respectively, represent the light character curves of the two lens

parts. This diagram is peculiar in the respect that the same character is not obtained in more than one direction.

In the arrangements according to Figs. 24-26 it is essential, that the values of speeds are in a simple relation to each other, e. g. 1:1, 1:2, 2:3 or the like. In this latter occasion, the speeds having a ratio of 2:3, the character will be repeated every second turning of the slower apparatus and every third turning of the faster apparatus.

Obviously the method of transmitting directed beams, above mentioned, can be used in connection with beams of all kinds. Here the use of beams of visible light has been shown, but it is assumed that equally well, e. g. radio beams or beams of other than visible light may be transmitted in the same manner.

Having thus described my invention, what I claim and desire to secure by Letters Patent is:

1. The method of producing signals with different signaling character in different directions, comprising the directional emission of a beam of radiant energy or the like from a source, rotating the directional emitting means to produce rotary movement of the beam in a predetermined plane, and periodically interrupting the rotary movement of said directional emitting means and oscillating said beam in the same plane during the period of interruption.

2. In signaling apparatus, the combination of a source of radiant energy, projecting means for producing a beam from the energy emitted by said source and for directionally controlling said beam in a plane, means for rotating said projecting means about a fixed axis at right angles to the direction of said plane, and means for periodically interrupting the rotational movement of said projecting means and oscillating said projecting means about said axis.

3. The method of emitting signals with different signaling character in different directions, which comprises projecting a beam of radiant energy or the like from a source, rotating said beam around said source substantially in a plane, interrupting the rotary movement of said beam when directed in a predetermined direction, and oscillating said beam in said plane during the period of interrupted rotary movement.

4. In signaling apparatus, a source of radiant energy, projecting means for producing a beam from the energy emitted by said source and for directionally controlling said beam within a plane, a rotary support for said projecting means, means for rotating said support in one direction about an axis at right angles to said plane and including a continuously rotating shaft, and mechanism interposed between said shaft and said support to reverse the rotary movement of said support from a certain position of its movement through a predetermined angle and thereafter continue the rotary movement past said position.

5. In signaling apparatus, a source of radiant energy, projecting means for producing a beam from the energy emitted by said source and for directionally controlling said beam within a plane, a rotary support for said projecting means, means for rotating said support in one direction about an axis at right angles to said plane and including a continuously rotating shaft, a friction driving connection between said shaft and said support, and means to effect slippage of said friction driving connection and periodically rotate said support through a predetermined angle in a direction opposite to the direction of rotation of said shaft.

6. A beacon having signaling means for emitting a signal in the form of a beam, means for rotating said signaling means to thereby rotate said beam in a plane around said signaling means, 5 means for interrupting the rotary movement of said signaling means in predetermined places of its revolution, and means for oscillating said signaling means during said periods of interrupted rotary movement to thereby oscillate said beam 10 within a predetermined angle in said plane.
7. A beacon having a source of light, projecting means for directing said light in a substantially horizontal direction in the form of a beam, a driving shaft, means for rotating said driving shaft, a cam disk mounted on said driving shaft and having a cam groove therein, a driven shaft connected to said light projecting means to transmit thereto the movements of said driven shaft, an arm mounted on said driven shaft, and a cam follower connected to said arm and engaging with said cam groove, said groove being so shaped as to rotate and periodically oscillate said driven shaft.
8. A beacon having a source of light, projecting means for directing said light in a substantially horizontal direction in the form of a beam, a driving shaft, means for continuously rotating said driving shaft, a friction coupling interconnected between said driving shaft and said projecting means, and means periodically engaging said projecting means to effect slippage of said coupling and thereby arrest the rotary movement of said projecting means at predetermined intervals.
9. A beacon having a source of light, projecting means for directing said light in a substantially horizontal direction in the form of a beam, a driving shaft, means for continuously rotating said driving shaft in one direction, a friction coupling interconnected between said driving shaft and said projecting means, and means periodically engaging said projecting means to effect slippage of said coupling and to reverse the rotary movement of said projecting means during predetermined intervals.

ERIK ROBERT PARSHBERG.
